JOHN SHIRLEY HOWKINS, OF FULHAM, LONDON, ENGLAND.

GROOVING-PLANE AND ANALOGOUS WOODWORKING-TOOL FOR GROOVING, RABBETING, BEADING, AND THE LIKE.

1,153,790.

Specification of Letters Patent. Patented Sept. 14, 1915.

Application filed May 23, 1914. Serial No. 840,575.

To all whom it may concern:

Be it known that I, JOHN SHIRLEY Howk-
kins, a subject of the King of Great Britain,
residing at 40 Waldemar Mansions, Walde-
mar avenue, Fulham, S. W., in the county
5 of London, England, have invented certain
new and useful Improvements in or Relating
to Grooving-Planes and Analogous Wood-
working-Tools for Grooving, Rabbeting,
10 Beading, and the like, of which the follow-
ing is a specification.

This invention has reference to grooving
planes and analogous wood working tools
for grooving, rabbeting, beading, inlaying
15 and the like.

One of the objects of the invention is to
provide a tool which can be used to produce
directly a well-finished groove across the
grain of either hard or soft wood, in such
20 a way that the groove as it is formed will
have smooth sides, and so that the tool can
work up to the end of the groove, which
will as produced be square or nearly so, and
require little or no finishing.

25 A further object is to produce a tool
which can be used for any of the above pur-
poses, and in which a large number of ad-
justments of the tool are possible. These
30 adjustments may be such as to enable the
cutters or tools to be inclined more or less
both transversely and also longitudinally
with regard to the tool. By means of the
sidewise or transverse inclination of the cut-
35 ters, grooves having their walls inclined to
one side or the other or undercut or re-
sembling dovetails, can be produced if de-
sired. On the other hand by varying the
40 inclination of the cutters longitudinally
(that is to say in a forward or backward di-
rection), their action can be better suited for
different kinds of works on which the tool is
being used.

According to the invention, the tool,
45 which in general appearance resembles a
carpenter's plow or beading plane, may have
its cutters formed in two pieces or lengths
lying one on the other, the upper one having
a chisel-like flat edge to produce the planing
50 action while the lower or rear one has a re-
cessed or horse-shoe shaped extremity, the
tips of which form a pair of sharp spurs
or teeth projecting down from or near the

corners of the top chisel and serving as
scribers or cutters to cut the edges of the
layer or shaving which is to be removed by
55 the top cutter or plane iron.

The two cutters may be mounted adjust-
ably in a slide or carrier which itself can
be raised or lowered in relation to the bot-
tom face of the plane or plow, and means
60 may be provided to enable their slope in-
clination in the direction of working to be
varied as desired. In addition to this the
under-portion or face of the latter may, near
65 each end, be attached to the body portion by
pivots, so that the body and underneath-
portion or working-face can be canted or
swivel sidewise, and thus produce grooves
70 or rabbets which are inclined to one side
or the other, or grooves or dovetails having
their sides oppositely inclined.

The spurs previously referred to may be
formed at the end of a piece of steel of tri-
angular section, having its lower end tapers
75 off and recessed out between the spur
points. These two spur points or cutters
may however be formed on separate pieces
or bars of steel, which when fitted in the tool
may be laid side by side or one above the
80 other each carrying one of the said spurs or
side cutters, the main cutter or grooving
iron being laid above them just as when they
are both formed on the same piece. One
spur only may be used in some cases.

In order that the invention may be clearly
85 understood and readily carried into effect,
reference will now be had by way of ex-
ample, to the accompanying drawings in
which:—

Figure 1 is a side view of one construc-
tion of the grooving plane, in which the cut-
ters or irons are mounted in a circular
swiveling head or carrier. Fig. 2 is a plan,
and Fig. 3 a front end view thereof. Fig. 4
is a vertical section through the tools or
90 cutters and their carrier block, taken lon-
gitudinally of the tools, Fig. 5 being a sec-
tion transversely to the tools on the line 5—5
of Fig. 1. Fig. 6 is an elevation of the car-
rier block, as seen from the top left hand
95 corner. Figs. 7 to 14 are detail views herein-
after referred to. Figs. 15, 16 and 17 are
100 views corresponding to Figs. 1, 2, and 3 but
showing a modified construction of tool in.

which the cutters are carried in an inclined rest or holder pivoted to the front of the frame. Fig. 18 is a detail section of a clamping device hereinafter referred to, taken on the line 18-18 of Fig. 15.

According to the example shown in Figs. 1 to 14, the body of the plow is approximately L-shaped in cross-section, the vertical portion a carrying the adjustable tool-slide b which engages vertical guides a^2 thereon, while the horizontal portion a^1 forms the working face. This plow body a is at its front and rear ends, mounted on pivots formed by screw-threaded pins a^3 , working in bearings a^4 on the base a^1 , this base extending from end to end like that of an ordinary plane. Thus the plow body can be swung or inclined sidewise or transversely more or less as desired as indicated by the chain lines Fig. 3. To facilitate this, a plate a^5 with a segment slot a^6 , is arranged near the front pivot, and the bent-round front a^8 of the plow body carries a clamping screw a^7 engaging (in the manner usual in such devices) in the slot a^6 to permit of fixing the body at the desired angle of adjustment. The aforesaid slide b is shown separately in face view and horizontal section in Figs. 8 and 9. It is pressed 20 tightly against its guides a^2 (see Figs. 1 and 2) by a pair of bolts b^1 passing through vertical grooves b^2 , one or both of which bolts may have springs b^5 interposed between them, or rather between their flanged ends 25 and the slide. This arrangement serves to give a yielding pressure sufficient to keep a good contact against the guides a^2 , but not enough to impede the vertical adjusting action of the slide b itself. The latter is adjusted vertically in any convenient way. In the present example this is effected by a traversing screw c adapted to be rotated by a nut c^1 (or it may be by a ratchet device or otherwise) and engaging in a projection or 30 nut b^8 on the slide b . The said slide b may be further guided by a projection or tongue piece engaging in a groove parallel with the screw c , as indicated at c^2 . d and d^1 are the working tools or cutters, the front or 35 upper of which d has either a square or slanting edge while the lower one d^1 has lateral cutting tips or prongs d^2 at its forward or lower corners to cut the edges of the shaving produced by the upper cutter, as before indicated. These prongs d^2 during the working of the tool, produce the smooth side walls of the groove or rabbet, as required. Only one prong might be used in some cases. The lower cutter d^1 acts as a 40 backing or support for the thinner top cutter d , and may be formed of steel rod of triangular section as seen respectively in plan, side view and end-view in Figs. 12, 13 and 14. The said cutters d d^1 are secured 45 in a hollow block or holder e extending

laterally from the slide, and are clamped tight by a movable yoke-piece f as shown separately in Figs. 10 and 11. The yoke is operated by a screw f^1 and nut f^2 . It works inside the projection and is adapted under 50 the action of the nut f^2 to draw the said tools tightly up against the top f^3 of an inclined mouth or opening extending across such projection or holder. Adjustable stops such as nuts d^3 working on screws d^4 , 55 are provided to regulate the amount by which the cutters d d^1 project from the holder, and to enable them to be adjusted relatively to each other as regards their overlap. In the example shown, the projecting bracket piece or holder e (see Figs. 4 to 6) is separate from the slide b and is mounted on a swiveling pin or pivot e^1 to enable it to be adjusted to vary the inclination of the cutters in a longitudinal direction, and then these latter, for some classes of work, may be brought into a vertical or nearly vertical position. The particular angle or adjustment is regulated by a pair of clamping bolts such as e^2 working in segmental slots e^3 in the well known manner. The tool is provided with a handle g at its rear end, and may have lugs h at each end to receive cross-bars or fence bars h^1 in the well known way with tools of this type. To 60 facilitate adjustment of these bars, the lugs may (see section shown in Fig. 7) have transverse screw-bolts h^2 with recesses h^3 in their sides into which the sides of the bars project. Then by tightening up the nuts of the bolts, the walls of the recess jam against the bars and provide a secure locking arrangement. By means of the screw c the slide b and with it the cutters d d^1 are fed downward gradually as the groove becomes deeper and deeper. To conveniently determine the final depth of the groove, an adjusting screw b^8 is fitted in a lug b^4 in one corner of the slide b . This screw is so adjusted that it will come against a stop or lug a^9 on the part a^8 of the body of the tool, and prevent further downward feeding of the slide b when the proper predetermined depth is reached.

Referring now to the example shown in Figs. 15 to 18 this comprises a tool having an inclined front edge forming the cutter-holder (e) provided with a yoke-piece f in which the adjustable cutters d d^1 are clamped by a set-screw f^1 in front of the tool. In this case the cutting tools rest on a backing iron or support d^5 resting on V-shaped bearers e^4 in the holder e , while the screw f^1 acts against a clamping piece i which fits on the cutter d and has lugs i^1 embracing the latter. Similarly lugs d^6 on the said piece d^5 fit against the edges of d and d^1 and keep them in position. The piece d^5 in turn works in the aforesaid inclined piece e and is adjustable by a traversing screw c , so as to vary 115 120 125 130 135

the depth of the cut and to feed the tool down into the work as the groove deepens. Independent adjustment of the front tool *a* may be effected by a set-screw *d*⁸ arranged as 5 shown in a lug at the top of the slide *d*⁵. In addition to this, the front portion *e* of the tool, may be arranged so that it can be set to different angles in a longitudinal direction by being mounted on a hinge or pivot *e*¹ 10 provided with a suitable fixing device, such as a curved segmental slotted wing *i*² and a clamping screw arrangement *i*³. The working face or bottom plate *a*¹ of the tool, may be arranged as before to pivot on a longitudinal axis, between a pair of pointed 15 pivot-screws *a*³ *a*³ to enable inclined grooves to be cut. Any convenient means, such as a screw *a*⁷ engaging a segmental slot *a*⁶ in a plate *a*⁵ may be provided, as before, to fix 20 the working face and body of the tool in their relative positions of adjustment or inclination.

Obviously the invention may be modified in various ways in carrying the same into 25 practice without departing from the general nature thereof.

What I claim as my invention and desire to secure by Letters Patent of the United States is:—

30 1. In a grooving plane or the like, having a working face of the ordinary kind, the combination of a planing iron or cutter tool set at an incline like that of an ordinary plane, a slide or carrier to support the same, 35 side cutters or spurs immediately below the cutting edge of the tool and means for feeding said tool down below the working face of the plane to any desired depth within the range of adjustment, substantially as de- 40 scribed.

2. In a grooving plane or the like, having a working face of the ordinary kind, the combination of an inclined planing tool or cutter, a slide or carrier to support the same, 45 means for feeding the tool down into the work, and one or more side cutters separate from the tool itself, having spurs for cutting the walls of the groove or recess, such spurs being arranged just below the cutting 50 edge of the tool, substantially as described.

3. In a grooving plane or the like, having a working face of the ordinary kind, the combination of an inclined planing tool or iron for forming the groove or recess, one or 55 more side cutters just below and behind the same having spurs for acting on the walls of such groove or recess, means for clamping the two kinds of cutters together, a slide or holder for carrying the two kinds of tools, 60 and a traversing screw for feeding them down below the face of the plane simultane-

ously to any desired depth within the range of adjustment, substantially as described.

4. In a grooving plane or the like provided with a working face of the ordinary kind, the combination of a planing iron or cutters to form the groove or recess, a side cutter for acting on the walls of said groove or recess, an adjustable cutter-holder in which said cutters are secured, a pivot or hinge for said holder, and means for adjusting the inclination of the holder in a longitudinal direction in the plane of the tool, substantially as described. 65

5. In a grooving plane or the like provided with a working face of the ordinary kind, the combination of a planing iron or cutter to form the groove or recess, a side cutter for acting on the walls of said groove or recess, an adjustable cutter-holder in which said cutters are secured, and means for inclining the cutters sidewise for undercut grooving or dovetailing, substantially as described. 70

6. In a grooving plane or the like provided with a working face of the ordinary kind, the combination of a planing iron or cutter to form the groove or recess, a side cutter for acting on the walls of said groove or recess, an adjustable cutter-holder in which said cutters are secured means for adjusting the inclination of the tools in a longitudinal direction, and means for adjusting their inclination in a sidewise direction, 90 substantially as described. 95

7. In a grooving plane or the like, the combination of a plane iron for forming the recess, a cutter for acting on the walls of said recess, a vertically movable slide mounted on guides on the body of said plane or the like, a swiveling tool holder mounted on said slide, and means for firmly clamping the cutters together in said tool holder, substantially as described. 100

8. In a grooving plane or the like, the combination of a plane-iron for forming the recess, a cutter for acting on the walls of said recess, a vertically movable slide mounted on guides on the body of said plane or the like, a swiveling tool holder mounted on said slide, pivots at the end of the plane body and near the working face, on which the said body can swivel to alter the sidewise inclination of the tools, substantially as described. 105 110 115

In testimony whereof I affix my signature in presence of two witnesses.

JOHN SHIRLEY HOWKINS.
